(57) CLAIM

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The broken line immediately adjacent to the bottom of the shaded area represents an unclaimed boundary of the design. The broken lines showing the triangular-shaped region and remainder of the shoe are for environmental purposes only and form no part of the claimed design.
